UNITED STATES PATENT OFFICE.

JOHN K. UHR, OF EAGLE GROVE, IOWA.

SCREEN AND STORM DOOR COMBINED.

SPECIFICATION forming part of Letters Patent No. 576,634, dated February 9, 1897.

Application filed June 5, 1896. Serial No. 594,460. (No model.)

To all whom it may concern:

Be it known that I, JOHN K. UHR, a citizen of the United States of America, residing at Eagle Grove, in the county of Wright and State of Iowa, have invented a new and useful Transformable Screen and Storm Door, of which the following is a specification.

My object is to facilitate the transformation of a door by interchanging solid panels and screens adapted for summer use.

My invention consists in the arrangement and combination of parts, as hereinafter set forth, pointed out in my claim, and illustrated in the accompanying drawings, in which—

Figure 1 shows a perspective of the door with parts broken away to show details of construction. Fig. 2 shows a transverse section of the door through the lower panel thereof.

Referring to the accompanying drawings, the reference-letter A is used to indicate the door-frame, which is of course of common construction.

The door proper is composed of a rectangular frame A and a central horizontal cross-piece A², which are of the ordinary kind, except for a rabbet B on the inner edge of each of said pieces, as required, to leave a rectangular opening at the top and bottom of the door having a rabbeted edge.

On the inner face of the door a bead or molding C is secured to slightly overlap the edges of the opening.

D is a straight bar fitted into a corresponding recess in the frame. Its ends are bent at right angles and adapted to slip under metal plates or catches D³, fixed to the movable panel and over recesses in the panel.

D³ is a handle extending outward from the center of the bar D through a slot in the door-frame in such a manner that the bar can be readily moved therewith, as required, to release the bent ends thereof from the recesses in the panel and the plates D², fixed over the recesses in the panel.

D⁴ represents a leaf-spring located behind the bar D in such a manner that it will normally retain the ends of the bar in the re-

cesses of the movable panel, as required, to lock the panel in its place. At the edge of 50 the opening opposite from the sliding bar two or more dowel-pins D⁵ are secured.

I have provided two panels for each opening, one of them solid and having its edges rabbeted to mate with the edges of the openings and so that the outer surface of the panel may be approximately flush with surface of the door. At one side of the panel openings F are provided for the reception of the dowel-pins, and at the opposite edge slots F² are 60 formed to admit the ends of the bar D.

It is obvious that this construction of the parts will provide a door in which either panel may be detached and a new one substituted without disturbing the other. This is of advantage when it is desired to have a glass panel above and a wooden panel below or a solid and a screen panel in the door at the same time, to control drafts through the door or to cut off vision, &c., and by means of the 70 concealed and flush joints of the panels in the door a neat and ornamental appearance is secured.

Having thus described my invention, what I claim as new therein, and desire to secure 75 by Letters Patent of the United States, is—

In a transformable door the frame A having a cross-piece A² and the inner edges of said parts rabbeted, a molding C fixed on the inside of the door to project inward from the 80 edges of the openings adapted to admit interchangeable panels and screens having recesses in their edges, a spring-actuated bar D having its ends bent at right angles to enter said recesses, fitted in a recess in the door-frame and provided with an integral arm D³ at its center that extends out through a slot in the frame that intersects said recess, and dowels D⁵ at the other side of the door frame and panel, arranged and combined as shown 85 90 and described for the purposes stated.

JOHN K. UHR.
